UNITED STATES PATENT OFFICE

2,522,860

HEATING SYSTEM

Paul Leroy Conaway, Wellsville, W. Va.

Application December 30, 1946, Serial No. 719,259

2 Claims. (Cl. 219—39)

1

This invention relates to a heating system and has for its primary object the economical heating of a room or a number of rooms within a building or like structure.

Another object of the invention is to enable but a single room to receive all of the heat output from a heating unit, thus to conserve energy and effect economies in operation.

The above and other objects may be attained by employing this invention which embodies among its features a plurality of heat ducts radially disposed about a common center, an air heating unit at the intersection of the axes of the ducts and means selectively to direct air heated by said heating unit into the ducts.

Other features include mounting the heating unit to rotate within a casing into which the ducts lead about the point of intersection of the axes of the ducts, and means to rotate the heating unit selectively to direct air heated thereby into the heat ducts.

In the drawings:

Figure 1 is a top plan view of a heating system embodying the features of this invention, certain portions being broken away more clearly to illustrate certain details of construction.

Figure 2 is a transverse sectional view taken substantially along the line 2—2 of Figure 1, showing the heating unit in the dotted line position illustrated in Figure 1, and

Figure 3 is a wiring diagram illustrating the means by which the swinging of the heating unit may be governed.

Referring to the drawings in detail, a heating unit designated generally 10 comprises a cylindrical shell or body 11 closed at opposite ends by heads 12. Formed at radially spaced intervals in the body 11 are ports 13, and coupled with the body 11 by flanges 14 are radially extending ducts 15 which will be understood lead to other ducts for carrying warm air to various different rooms of a building (not shown). Extending through the topmost head 12 in concentric relation with the periphery thereof is an opening 16 on opposite sides of which are mounted suitable journal bearings 17 in which the drive shaft of the heating unit to be more fully hereinafter described is mounted to rotate. Mounted in axial alignment with the opening 16 on the inner face of the opposite head 12 is a disc 19 of insulating material, and mounted on the inner face of the disc is a slip ring 20 for a purpose to be more fully hereinafter described. The entire heating device 10 is adapted to be supported beneath a floor or the like on suit-

able brackets 21 though it is to be understood that if so desired, the device may be supported in any suitable manner and in any suitable position.

5 Mounted for rotation in the bearings 17 is a shaft 22 carrying adjacent its outer end a gear 23 which has meshing engagement with a gear 24 carried by the drive shaft of a prime mover 25 such as an electric motor which is supported on 10 a suitable bracket 26 rising from the upper head 12 as will be readily understood upon reference to Figure 2. The lower end of the shaft 22 is connected as by a coupling 27 to a tubular casing 28, and mounted on suitable brackets 29 at 15 one end of the tubular casing is a fan motor 30 carrying on its drive shaft a fan 31 which is so arranged that when the motor is energized a blast of air will be introduced into the casing 28. One terminal of the motor 30 is connected 20 by an insulated conductor 32 to a contact 33 which is insulated from the casing 28 in any suitable manner and carries a spring finger 34 which bears upon the slip ring 20. The opposite terminal of the fan motor 30 is grounded in 25 a conventional manner.

Mounted within the casing 28 in line with the blast of air created therethrough by the fan 31 is a lamp socket 35, one terminal of which is grounded while its opposite terminal is coupled to a spring finger 36 which like the finger 34 rides on the slip ring 20, and screwed into the socket 35 is a conventional electrical heating element 37 which is held in the path of the air blast so that air passing therearound will become 30 heated. A nipple 38 extends from the end of the casing 28 opposite the fan 31 and terminates adjacent the inner face of the cylindrical body 11. It will thus be seen that when the nipple 38 aligns with an opening 13 a blast of warm air will 35 be directed through the duct 15 aligning therewith and thence to the space to be heated.

In order conveniently to bring the nipple 38 into alignment with the desired nipple 15 the motor 25 has one side coupled through a line 40 leading to a source of power while the other side of the motor is coupled through a conductor 40 to a series of switches 41, each of which is located in a room or other space to be heated. The slip ring is connected through a suitable insulated 45 conductor 42 to a suitable source of electrical energy, the other terminal of which is grounded so that energy will flow through the heating unit 37 and fan motor 30 in order that air driven through the casing 28 and contacting the heating unit 37 will become heated. It will be under-

stood of course, that any suitable switch means (not shown) may be interposed in the circuit to govern the operation of the motor 30 and the heating unit.

When one of the switches 41 is manually closed, it is obvious that the motor 25 will be set into operation to cause the pinion 24 thereof to rotate the drive gear 23 and move the shaft 22 until the nipple 38 aligns with an opening 13. With the circuit closed through the fan motor 30 and the electrical heating unit 31, it will be obvious that a blast of warm air will be introduced into the nipple 15 with which the nipple 38 aligns, and the air conducted through the ducts leading from the nipple 15 into the space to be heated. The air blown into the casing 28 comes from the other spaces or rooms through the ducts 15 which are not aligned with ducts 38. It will be understood of course, that when the nipple 38 aligns with the duct 15 the switch 41 for that particular duct will be opened, thus stopping further movement of the nipple 38 about the axis of the shaft 22. When it is desired to heat another space connected with the same system, it is only necessary to throw the switch 41 located conveniently to that space in order to swing the nipple 38 into alignment with the proper duct and then discontinue the flow of electrical energy through the motor 25, thus keeping the nipple 38 in alignment with the desired duct. In this way, it will be obvious that a group of spaces may be selectively heated simply by the manipulation of the switches 41.

While in the foregoing there has been shown and described the preferred embodiment of this invention it is to be understood that minor changes in the details of construction, combination and arrangement of parts may be resorted to without departing from the spirit and scope of the invention as claimed.

5

I claim:

1. In a space heating system, a substantially circular drum having radial openings extending through its side wall, an air heating unit mounted within the drum to rotate about the center thereof, a duct extending radially from the air heating unit and means to rotate the heating unit selectively to move the duct into registration with an opening in the drum.

2. A space heating system comprising a circular drum having radial openings extending through its side wall, an air heating unit mounted within the drum to rotate about the center thereof, a duct extending radially from the air heating unit, and means to rotate the heating unit selectively to move the duct into registration with a radial opening in the drum, said heating unit including a housing, a heating coil in said housing in alignment with said duct, a fan in said housing behind said heating coil, a slip ring in the bottom wall of said drum operatively connected to a source of electric current, and spring finger contacts operatively engaging said slip ring and connected to said heating coil and said fan.
